United States Patent Office.

WARREN PORTLOCK, OF PLEASANT GROVE, AND JOHN H. SMITH, OF
TOOLESBOROUGH, IOWA.

Letters Patent No. 74,128, dated February 4, 1868.

IMPROVEMENT IN FLOOR-CLAMPS.

The Schedule referred to in these Letters Patent and making part of the same.

TO ALL WHOM IT MAY CONCERN:

Be it known that we, WARREN PORTLOCK, of Pleasant Grove, in the county of Des Moines, and JOHN H. SMITH, of Toolesborough, in the county of Louisa, and State of Iowa, have invented Improvements in the Construction of Floor-Clamps; and we do hereby declare that the following is a full and exact description thereof, reference being had to the accompanying drawings, and to the letters marked thereon.

The nature of our invention consists, first, in constructing floor-clamps in such a manner that the distance between the shanks can be changed, according to the width of the joist; second, that they can be adjusted, removed, or transferred almost instantly; third, in constructing floor-clamps so as to obtain closer joints between the floorings; fourth, in constructing floor-clamps so as to be applicable at places of small space.

To enable others skilled in the art to make and use our invention, we will now proceed to describe its construction and operation.

We construct a wooden lever, A, and adjust to one end two iron shanks, B B, bolted thereon in such a manner that by loosening the nut of the bolt the shanks may be let apart to suit the width of the joist. On the lower end of these shanks we adjust two catching-jaws, E, in such a manner as will allow them to swing on the shanks. The front ends of these jaws are sharpened, so as to allow them to penetrate the wood and obtain a secure hold. The rear ends of these jaws have a projecting knee, on which the spring J, wound around the small projection of the shanks, presses in such a manner as to throw the front of the catching-jaws always against the wood between the jaws. In using this tool for the purpose of laying flooring, the shanks obtain a vertical position on each side of the joist G, the springs I pressing the jaws E against it, and into which they penetrate and obtain secure hold. By pulling the lever A towards the operator, the power or fulcrum is against the flooring L, which are thus pressed close to each other. The back brace C, hinged to and between the shanks, holds the lever in position until the flooring is permanently fastened. This back brace is made with a knee or stub-joint, which will bend by giving it a slight pressure on the under side, and thus allow the lever to come back. D D are two small levers, connected with the jaws E. By passing the hand down the main lever A, the small levers D D can be pressed together, and the jaws E are thus pressed open and out of the joist, and easily transferred to the next joist. To keep the jaws open, a bow, O, is attached over the small levers D, which allows them to come but a certain distance apart, and consequently prevents the spring I from pressing the front of the jaws entirely together. In a similar manner sidings, ceilings, boat-bottoms can be pressed together and held in place until fastened.

When the end of back brace or prop is set on the joist to hold the lever permanent against the flooring, the resisting elasticity of the flooring causes the end of the prop or back brace to enter the joist, which allows the clamp or lever to come back an equal distance, and hence no really close joint can be produced; but by providing the back brace with a knee or stub-joint, C, we reduce its length by bending it at the knee, and, after pressing the flooring as close as possible, we adjust the back brace and straighten it; thus the amount which penetrates the joist is obtained in the length of the back brace, and hence the flooring is kept as close as before setting the back brace. In removing a prop or back brace, without a knee or stub-joint penetrated into the joist, as described, it usually requires considerable strength and time for its removal, whilst a back brace, with knee or stub-joint, can be removed quickly and easily by bending it, thus withdrawing the point in the manner it entered the joist.

Claims.

We claim as our invention, and desire to secure by Letters Patent—

1. The back brace C, provided with a knee or stub-joint, constructed substantially in the manner and for the purpose as set forth.
2. The small levers D D, constructed and operating together substantially in the manner as above shown and specified.

WARREN PORTLOCK,
JOHN H. SMITH.
